UNITED STATES PATENT OFFICE

166,754

TIME STAMP CASE

Michael Juhas, Torrington, Conn., assignor to General Time Corporation, New York, N. Y., a corporation of Delaware

Application March 10, 1952, Serial No. 18,837

Term of patent 14 years

(Cl. D64—10)

To all whom it may concern:

Be it known that I, Michael Juhas, a citizen of the United States, residing at Torrington, in the county of Litchfield and State of Connecticut, have invented a new, original, and ornamental Design for a Time Stamp Case, of which the following is a specification, reference being had to the accompanying drawing, forming a part thereof.

I claim:

The ornamental design for a time stamp case, substantially as shown.

MICHAEL JUHAS.
